(No Model.)

J. D. MILLER.

AUTOMATIC CAR BRAKE.

No. 292,246.

Patented Jan. 22, 1884.

UNITED STATES PATENT OFFICE.

JOHN D. MILLER, OF BIG SANDY, ASSIGNOR OF ONE-THIRD TO THOS. M. MIERS, OF DALLAS, TEXAS.

AUTOMATIC CAR-BRAKE.

SPECIFICATION forming part of Letters Patent No. 292,246, dated January 22, 1884.

Application filed June 11, 1883. (No model.)

To all whom it may concern:

Be it known that I, JOHN D. MILLER, of Big Sandy, in the county of Upshur and State of Texas, have invented certain new and useful Improvements in Automatic Car-Brakes; and I do hereby declare the following to be a full, clear, and exact description of the invention, such as will enable others skilled in the art to which it pertains to make and use it, reference being had to the accompanying drawings, which form part of this specification.

My invention relates to an improvement in automatic car-brakes; and it consists, first, in the combination of the draw-heads, suitable levers which are connected thereto, connecting-rods which extend from opposite ends of one of these levers, and a partially-rotating shaft provided with suitable slotted cams, which cams are attached to the brake-beams, so that when the draw-heads are forced inward or drawn out the brakes will move out of contact with the wheels; second, in the combination, with the slotted cams and a mechanism for moving them, of the rods which are connected thereto, and which pass through the brake-beams, the sliding sleeves, the springs, and the nuts upon the ends of the rods; third, in the combination of the endwise-moving draw-heads, suitable intermediate mechanism attached thereto, and the springs, the movement of the draw-heads in either direction being made to operate the brakes, all of which will be more fully described hereinafter.

The object of my invention is to connect suitable mechanisms with the draw-heads for the purpose of connecting them with the brakes, so that any movement of the draw-head in either direction will put on or take off the brakes, as may be desired, and thus make the action of the brakes entirely automatic.

Figure 1 is an inverted view of a brake mechanism embodying my invention. Fig. 2 is a side elevation of the same. Fig. 3 is an end view.

A represents the frame of the car; B, the trucks; C, the car-wheels, and D the brakes which are made to bear against the wheels.

The draw-heads E may be of any suitable construction, and are here arranged in suitable

guides, F, so that they can move freely back and forth, for the purpose of operating the brakes.

Rigidly secured to the under side of each end of the frame is a metallic support, G, upon which the two levers H are pivoted. The inner end of the lever I is pivoted directly to the under side of the draw-head, so that the draw-head as it moves back and forth will operate the lever, and this lever in turn communicates motion to the second lever, H, which is pivoted to it.

In order to give a longer or shorter throw to the connecting-rods J, which are attached to the lever H, there is a slot made through the center of the lever I, so that the pivot or fulcrum K of this lever can be adjusted back and forth. When this pivot is moved toward the draw-head, a longer stroke is given to the connecting-rods J, and when the pivot is moved toward the lever H a shorter movement is imparted to the rods. As the brakes are operated by the connecting-rods J, it will readily be seen that in this way the movement given to the brakes can be regulated at will. The connecting-rods J are attached to opposite ends of the lever H, and extend diagonally across under the frame of the car, and have their ends attached to opposite ends of the arm or lever M, which is fastened to the partially-rotating shaft N, located at or near the middle of the car. These rods J, being attached to opposite ends of the lever H, are caused to push and pull in opposite directions, for the purpose of turning the shaft N at every movement of either one or both of the draw-heads. This shaft N is pivoted in a suitable frame-work, O, which is secured to the under side of the frame of the car, and has secured to it, near its lower end, the arm or lever P, which has a slotted cam, Q, formed upon each of its ends. These cams may either be of the form here shown or any other that may be preferred. By means of the curved slot the cams are made to operate the rods which connect them with the brake-beams, whether the draw-heads are forced inward or pulled outward. When the draw-heads are forced inward, as when the cars run together or are being backed, the connecting pin, stud,

or projection R, secured to the rod S, and which passes through the slot in the cam, will be moved toward one end of the slot, and when the draw-heads are drawn outward, as when 5 the train is in motion, the pin, stud, or projection will move up into the other end.

Secured to the frame in which the partially-rotating shaft is pivoted are the supports T, through which the rods S pass at their inner 10 ends. The outer ends of these rods pass through the brake-beams U. Upon each rod are placed the sliding sleeve V, the spring W, and the nut X. The sleeve serves to compress the spring against the brake-beam when the 15 rod S is moved endwise, and the nut serves to shorten the rod, so as to cause a greater or less pressure of the spring to be exerted against the rod, and thus apply the brake with greater or less force. Each brake-beam is 20 suspended from the under side of the frame by means of the straps, springs, or other supports, Y, and the brakes attached to this beam are always held in contact with the wheels when the draw-head is in its normal position. These 25 springs will have sufficient power to force the brakes against the wheels with force enough to hold the car in place upon the rails of any ordinary grade. As soon as a number of cars are fastened together and the train is set in 30 motion, the draw-heads are pulled outward or forced backward, for the purpose of throwing the brakes clear of the wheels, according as to whether the train is being pulled or backed. If the train is being pulled by the locomotive, 35 the draw-heads are pulled outward far enough to operate the levers and withdraw the pressure of the brakes from the wheels, and in case the train is being backed the draw-heads are forced inward; but in either case the connecting-rods 40 J are made to move the partially-rotating shaft

and release the wheels from the brakes. As soon as the train stops, the pull or push is released from the draw-heads, and the brakes are at once applied by means of the springs.

From the above description it will be seen 45 that the brakes are entirely automatic in their operation, and hence the train is made to do its own braking.

I do not limit myself to the precise construction here shown, for the levers may be connected to the draw-heads in different ways. The manner here shown is most preferable, but is only one of a number of different arrangements.

Having thus described my invention, I 55 claim—

1. In an automatic car-brake, the combination of the endwise-moving draw-heads, the levers connected thereto, the connecting-rods attached to the levers, a partially-rotating 60 shaft provided with cams, the connecting-rods, springs, and brake-beams, substantially as shown.

2. The combination of the endwise-moving draw-head, the levers H I, the connecting-rods, 65 and the intermediate mechanism for operating the brake-beams, the lever I being slotted so that its pivot can be adjusted endwise, substantially as described.

3. The combination, with the partially-rotating shaft provided with cams, and an operating mechanism, of the rods, the springs, and the sleeve, substantially as set forth. 70

In testimony whereof I affix my signature in presence of two witnesses.

JOHN D. MILLER.
